(57) **CLAIM**

The ornamental design for a window screen kit as shown and described.

DESCRIPTION

FIG. 1 is a perspective view of a window screen kit showing my new design;

FIG. 2 is a perspective view of a window screen body of the window screen kit, shown separately for ease of illustration;

FIG. 3 is another perspective view thereof;

FIG. 4 is a front elevational view thereof;

FIG. 5 is a rear elevational view thereof;

FIG. 6 is an enlarged view of portion 6 shown in FIG. 2;

FIG. 7 is a perspective view of a first fixing component of the window screen kit, shown separately for ease of illustration;

FIG. 8 is another perspective view thereof;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof;

FIG. 14 is a bottom plan view thereof;

FIG. 15 is a perspective view of a second fixing component of the window screen kit, shown separately for ease of illustration;

FIG. 16 is another perspective view thereof;

FIG. 17 is a front elevational view thereof;

FIG. 18 is a rear elevational view thereof;

FIG. 19 is a left side elevational view thereof;

FIG. 20 is a right side elevational view thereof;

FIG. 21 is a top plan view thereof;

FIG. 22 is a bottom plan view thereof;

FIG. 23 is a perspective view of a third fixing component of the window screen kit, shown separately for ease of illustration;

FIG. 24 is another perspective view thereof;

(Continued)

FIG. 25 is a front elevational view thereof;
FIG. 26 is a rear elevational view thereof;
FIG. 27 is a left side elevational view thereof;
FIG. 28 is a right side elevational view thereof;
FIG. 29 is a top plan view thereof;
FIG. 30 is a bottom plan view thereof;
FIG. 31 is a perspective view of a fourth fixing component of the window screen kit, shown separately for ease of illustration;
FIG. 32 is another perspective view thereof;
FIG. 33 is a front elevational view thereof;
FIG. 34 is a rear elevational view thereof;
FIG. 35 is a left side elevational view thereof;
FIG. 36 is a right side elevational view thereof;
FIG. 37 is a top plan view thereof;
FIG. 38 is a bottom plan view thereof;
FIG. 39 is a perspective view of a fifth fixing component of the window screen kit, shown separately for ease of illustration;
FIG. 40 is another perspective view thereof;
FIG. 41 is a front elevational view thereof;
FIG. 42 is a rear elevational view thereof;
FIG. 43 is a left side elevational view thereof;
FIG. 44 is a right side elevational view thereof;
FIG. 45 is a top plan view thereof; and,
FIG. 46 is a bottom plan view thereof.

The dash-dash broken lines and the areas within the dash-dash broken lines depict portions of the window screen kit that form no part of the claimed design. The dot-dash broken

lines represent the boundary of the enlarged portion and form no part of the claimed design.
